UNITED STATES PATENT OFFICE.

JEROME B. SECOR, OF CHICAGO, ILLINOIS.

DESIGN FOR TREADLE FOR SEWING-MACHINES.

Specification forming part of Design No. 5,231, dated August 22, 1871.

To all whom it may concern:

Be it known that I, JEROME B. SECOR, of Chicago, in the county of Cook and State of Illinois, have invented and produced a new and useful Design for Treadles for Sewing-Machines, of which the following is a specification:

The nature of my design is fully represented in the accompanying drawing, to which reference is made, of which—

Figure 1 is a top or plan view, and Fig. 2 a side elevation.

The scroll-work is light, and gives a graceful appearance to the treadle, while at the same time it forms a frame sufficiently strong to support the flattened bars which support the feet in operating the machine. The treadle is slightly curved, so as to correspond somewhat to the shape of the sole of the foot, so that the pressure is distributed as nearly as possible over the whole sole of the foot, as may be observed by reference to the side elevation shown in the drawing, Fig. 2. The driving-rod may be hinged or pivoted to a projection formed by the scroll-work, which extends

laterally sufficiently far to hold the driving-rod at a convenient distance from the knees and legs, as shown in the top or plan view. The bars upon which the feet of the operator are intended to rest are flattened upon their upper surface, so as to furnish a comfortable resting-place for the feet while the treadle is being operated, and the braided or twisted bars which cross them relieve them of a plainness of appearance. The treadle is pivoted or has bearings upon a shaft or rod near its rounded end, at the projection shown near the lower end of the side elevation.

The design is such that it may be cast in one piece, and it is ornamented, and easily and comfortably operated. I make no claim except as for a design.

I claim as my invention—

The design for treadles for sewing-machines, as shown.

JEROME B. SECOR.
